BACK DUMP MECHANISM

Leo Berner, Huntington Park, and Claude B. Ogle, Los Angeles, Calif., assignors to Atlas Scraper and Engineering Co., Bell, Calif., a corporation of California

Application September 5, 1939, Serial No. 293,416

7 Claims. (Cl. 37—132)

Our invention relates to earth scrapers, and particularly to an earth scraper having a unique back dump mechanism whereby upon rearward movement of the scraper the bowl is caused to rotate in a rearward direction.

Our invention may be used on different types of earth scrapers which are in general use in the industry and has utility where it is desired to have an earth scraper in which the load in the bowl may be dumped rearwardly behind the scraper, such, for example, as over an embankment which lies rearwardly of the scraper. Our invention is also of utility on scrapers where the mechanism for raising the bowl from digging to carrying position may not be adequate to move the bowl when it is heavily loaded or where no such means is provided. In accordance with the teachings of our invention, we provide means whereby the bowl may be locked to the wheels of the scraper so that when the scraper is moved rearwardly the bowl is rotated in a rearward or reverse direction. In this way the bowl may be moved from digging to carrying position or may be rotated a complete revolution, thus causing the load of dirt to be dumped rearwardly from the scraper-bowl.

It is an object of our invention to provide an earth scraper having a back dumping mechanism of the character referred to in the preceding paragraphs which is mounted on trunnions or axles of the bowl and which cooperate with the wheels which are rotatable on the axles, whereby the bowl and wheels are locked together in order that upon rearward movement of the scraper the bowl will be rotated in a rearward direction.

It is a still further object of our invention to provide a scraper having wheels which are positioned outside the side bars of the draft frame and in which the back dump mechanism is placed between the side bars and the wheels.

It is a still further object of our invention to provide a scraper having a back dump mechanism of the character referred to in the preceding paragraphs in which a part of the back dump mechanism extends into the bearing on the side bar of the draft frame and acts as a securing means whereby this part of the back dump mechanism is secured to the axle and also acts as a journal within the side bar bearing.

It is a further object of our invention to provide a combination in which the wheels are placed between the bowl and side bars of the frame and in which the back dump mechanism is located between the bowl and wheels.

It is a further object of our invention to pro-

vide a back dump mechanism useful on wheel scrapers or the like which is of simple and sturdy construction and which is adapted to be mounted on the exterior of the bowl.

Other objects and advantages of our invention will be brought out during the course of the following detailed description of alternative forms of our invention.

Fig. 1 is a fragmentary plan view of an earth 10 scraper incorporating the features of our invention. This view shows the relation between the back dump mechanism, the draft frame, and bowl and wheels.

Fig. 2 is an enlarged fragmentary view, partly 15 in section, illustrating the back dump mechanism of our invention.

Fig. 3 is a section taken on the line 3—3 of Fig. 2.

Fig. 4 is a sectional view taken on the line 20 4—4 of Fig. 2.

Fig. 5 is a fragmentary elevational view illustrating an alternative form of our invention.

Fig. 6 is a sectional view taken on the line 25 6—6 of Fig. 5, and showing our alternative form of back dump mechanism.

Referring to the drawings in detail, Fig. 1 diagrammatically illustrates the scraper in plan view. The numeral 11 represents a scraper bowl having a forward cutting edge 12. Secured to 30 and extending outward from end plates 14 of the bowl 11 are axially aligned axles, spindles, or stub shafts 15 on which wheels 16 are rotatable. The scraper has a draft frame including side bars 17, the rearward ends of which have bearings 18 which surround the axles 15.

We have not illustrated other details of construction of the rotary scraper due to the fact that such details are well known in the art and due to the fact that our invention resides more 40 particularly in the back-up mechanism which is disclosed in detail herein and which may be applied to any of the different scrapers now in use. As an example of the scraper to which our invention may be put, reference is made to the patent to Hyrum Ricks, No. 1,834,110, issued December 1, 1931, and also to our copending application for Scraper, Serial No. 294,246, filed September 11, 1939.

Referring more particularly to Figs. 2 to 4 inclusive, we will now describe the details of construction of those parts which constitute the essence of our invention. The axles 15, which extend outward from the end walls 14 of the bowl, are welded to axle plates 20, which are in turn secured to the end walls 14. It will be under-

stood that in the preferred form of our invention there are two back dump mechanisms 21 positioned between the side bars and the wheels, which are relatively lefthand and righthand structures. For convenience, we have shown in detail, and will describe, the righthand back dump mechanism, it being understood that the lefthand back dump mechanism is identical thereto.

The axle 15 extends through the bearing 18 and is surrounded by a sleeve 23 which constitutes a part of a latch supporting means which also includes a latch housing 24. This sleeve 23 is non-rotatably secured to the axle 15 by means of keys 25 each having a head 26 at its outer end. The bearing 18 includes a removable bearing liner 27 having an outer flange 28. The sleeve 23, as will be seen, acts as a journal rotatably supported in the liner 27 of the bearing 18 and also acts as a means for securing the latch housing 24 to the axle 15.

The latch housing 24 includes a relatively heavy wall 30 which has an opening 31 formed in it into which the outer end of the sleeve 23 extends, these parts being rigidly secured together such as by welding. The latch housing also includes an outer wall 32 which is supported in spaced relation to the inner wall 30 and is secured thereto by a peripheral or perimetric wall 33, which walls cooperate to provide a latch chamber 34.

Positioned in the latch chamber 34 is a latch 36, which is pivotally supported on a pivot shaft or pin 37 supported by the walls 30 and 32, as shown. The latch 36 has a lower engaging end 38 and an upper weighted end 39 and is movable between unlatched position, as shown by full lines in Fig. 2 into latched position as shown by dotted lines 40 in Fig. 2. The unlatched position of the latch 36 is determined by an adjusting pin 41 which is adjustable in slots 42 formed in the inner and outer walls 30 and 32. The purpose of providing this adjustment is so that the latch 36, when in unlatched position, will be supported in such a position that it requires but little movement of the latch supporting means in a clockwise direction to throw the latch 36 off bearing so that it will, by the action of gravity, move into latched position.

The outer end 44 of the axle 15 is of reduced diameter and rotatably supports a wheel hub 45. This wheel hub 45 is restrained from axial removal by means of a retainer washer 46, which is placed on the stub end 47 of the axle 15 and held in place by a cotter-key 48. The hub 45 is adapted to support an inner sleeve 50 of the wheel 16 to which sleeve 50 spokes 51 of the wheel are secured. Adapted to be secured onto the outer end of the hub 45, so as to enclose the stub end 47, washer 46, and cotter-key 48, is a hub cap 52. This hub cap 52 also acts as a means for securing the sleeve 50 to the hub 45. This securing is effected by means of wedge means 53 which are forced into the sleeve 50, thus causing the sleeve 50 to be rigidly supported on the wedge means 53 and the inner conoidal portion 55 of the hub 45.

The inner end of the hub 45 is provided with an abutment means 58 which provides a series of alternate abutments or teeth 59 and spaces 60 circularly aligned at the lower part of the latch housing 24, the teeth 59 being in a position to be engaged by the latch 36 when in latched position. To relieve the latch support-

ing means from wear, a wear plate 62 is positioned between the inner end of the hub 45 and the outer end and outer face of the sleeve 23 and inner wall 30. To receive the heads of 5 the keys 25 cavities 64 are provided in the inner end of the hub 45.

As is well known in the art, earth scrapers of the type to which our invention may be applied are pulled over the surface of the ground by means of a tractive vehicle connected to the draft frame. When it is desired to gather earth the bowl is rotated into digging position, this being accomplished by causing the bowl to rotate so that the blade 12 thereof drops below the surface over which the scraper is being moved. When the bowl is filled with earth, the bowl is then rotated in a reverse direction and into a carrying position. The bowl is maintained in this position until it is desired to dump the earth. If it is desired to dump the earth ahead of the bowl and to level it over the ground, the bowl is permitted to rotate in a forward direction, thus dumping the earth ahead of the blade 12. All of these operations thus referred to are well known in the industry and mechanisms for accomplishing such operations are well known and illustrated in the patent and copending application referred to heretofore.

When our invention is employed on a scraper it is possible to employ the rearward movement of the tractive vehicle to raise the bowl from digging to carrying position and to rotate the bowl in a rearward or reverse direction to cause the earth to be dropped rearwardly in back of the scraper. This action is accomplished as follows: 30 In Fig. 2 the parts are shown in full lines in the positions which they occupy when the bowl 11 is in carrying position. At this time the center of gravity of the weighted end 39 is to the left of a vertical plane extending through the axis of the pin 37, this causing the latch 36 to be maintained in unlatched position against the adjusting pin 41.

In order to bring the back dump mechanism into operation, the operator of the scraper, by mechanisms commonly provided and as illustrated in the patent and copending application referred to heretofore, moves the bowl in a clockwise direction, thus causing the latch supporting means to rotate in a clockwise direction. When the parts have moved sufficiently to move the center of gravity of the weighted end 39 to the right of the vertical plane extending through the axis of the pin 37 the latch 36 will move by gravity into latched position as shown by dotted lines 40 in Fig. 2. The parts may be adjusted so that this movement of the latch from unlatched to latched position will occur at or before the time the bowl reaches its digging position. During forward movement of the scraper, the hub 45 rotates in a clockwise direction and the teeth 59 merely pass by the engaging end 38 of the latch 36 due to the tangential arrangement thereof. It will be seen, therefore, that the moving of the latch into latched position has no effect whatsoever while the scraper is stopped or moving in a forward direction.

With the parts in the positions described the operator can use the reverse movement of the tractive vehicle to rotate the bowl 11 in a rearward direction. When the scraper is moved rearwardly the wheels 16 are rotated rearwardly relative to the axles 15 until one of the teeth 59 engages the end of the engagement end 38 70 of the latch 36. At this time the wheels 16 be-

come locked to the axles 15 and at this time there can be no relative movement between the wheels 16 and bowl 11 in a rearward direction. It will, therefore, be seen that upon further rearward movement of the scraper the rearward or anticlockwise motion of the wheels 16 will be transmitted through the back dump mechanism to the axle and from the axle to the bowl. Therefore, as the scraper is moved rearwardly the bowl can be moved into a carrying position. This function is, of course, utilized on scrapers which do not have control mechanisms or means capable of moving the loaded bowl from digging to carrying positions. By the simple mechanism which we have provided relatively complicated mechanisms for moving the bowl from digging to carrying positions can be eliminated.

By continuing the reverse movement of the scraper the bowl may be completely rotated so that the earth may be dumped from the rear of the bowl. This type of dumping is indispensable where it is necessary to dump the earth over an embankment. By the arrangement of our invention the scraper may be moved rearwardly to the edge of the embankment with the bowl in carrying position and the dumping action so timed by means of lowering the lip of the bowl to the ground in order to move the latch into latched position that as the wheels reach the edge of the embankment the bowl is rotated into a rearward dumping position.

Upon forward movement of the scraper the latch 36 is, of course, released and the teeth 59 will move by the engagement end 38 and when the parts are rotated to normal carrying position the latch 36 will again assume an unlatched position as shown in Fig. 2.

In Figs. 5 and 6 we have illustrated an alternative form of our invention. In describing this form of our invention the parts which are similar to those in the first form of our invention will be given the same numeral but will have the suffix *a* added to the numeral. The bowl *11a* has side walls *14a* from which axles *15a* extend. Side bars *17a* have bearings *18a* which are at the outer ends of the axles *15a*, and in which the axles rotate. Rotatable on the axles *15a* between the side walls *14a* of the bowl and the side bars *17a* are hubs *45a* on which wheels *16a* are mounted in substantially the same manner as illustrated in Figs. 1 to 4, inclusive. The inner end of each hub *45a* has an abutment means which provides teeth *58a*, each abutment means being located between a side wall *14a* of the bowl and a wheel *16a*. Secured to each side wall of the bowl in an eccentric position is a pivot shaft or pin *37a* which supports a latch *36a*.

In this form of our invention the operation of the parts are substantially the same as in the first form. When the bowl is in carrying position the latch 36a is so weighted that it is retained in an unlatched position. When the bowl is swung into a digging position, as shown in Fig. 5, the latch 36a will swing into latched position and upon a rearward movement of the scraper will be engaged by one of the teeth 58a which will result in the wheels 16a being locked from rotation relative to the bowl and shaft with the result that upon rearward movement of the scraper the bowl will be rotated in a reverse direction.

It will be understood that in this form of our invention as in the preferred form back dump mechanisms are preferably provided between each of the wheels and the bowl although if de-

sired only one need be used although this would place a considerable twisting strain in the apparatus.

It is believed that the manner in which we accomplish the features and objects of our invention will be well understood from the preceding detailed description of a preferred form of our invention. We realize that the principle of our invention may be employed in different structures and we therefore wish our invention to be broadly construed to include its different mechanical equivalents in accordance with the spirit and scope of the appended claims.

We claim as our invention:

- 15 1. In an earth scraper, the combination of: a bowl; axles extending outward from said bowl; a draft frame connected to said axles; wheels rotatable on said axles outside said draft frame; and latch means positioned between said draft frame and one of said wheels and operative for locking said last mentioned wheel from rotation rearwardly relative to the axle on which it is mounted.

20 2. In an earth scraper, the combination of: a bowl; axles extending outward from said bowl; a draft frame connected to said axles; wheels rotatable on said axles outside said draft frame; a pivot eccentrically supported by one of said axles; a latch on said pivot swingable between latched and unlatched positions; and an abutment on one of said wheels engageable with said latch when said latch is in latched position.

25 3. In combination in an earth scraper, a back dump mechanism which includes: an axle extending outwardly from one side of the bowl of the scraper; a housing eccentrically mounted on the axle of said scraper; a wheel on said axle on one side of said housing; a draft frame engaging said axle on the other side of said housing; a latch pivotally supported in said housing, said latch having a latched and an unlatched position; and an abutment on the wheel of said scraper which is rotatable on said axle, said abutment being engageable by said latch when said latch is in latched position.

30 4. In combination in an earth scraper: a bowl; an axle secured to said bowl; a draft frame having a bearing surrounding said axle; a latch-supporting means having a sleeve secured to said axle within said bearing and acting as a journal; a wheel rotatable on said axle; abutment means on said wheel; and latch means mounted on said latch supporting means movable into engagement with said abutment means.

35 5. In combination in an earth scraper: a bowl; an axle secured to said bowl; a draft frame having a bearing surrounding said axle; a latch-supporting housing outside said draft frame and having a sleeve secured to said axle within said bearing and acting as a journal; a wheel rotatable on said axle; abutment means on said wheel; and gravity operated latch means mounted within said latch supporting housing movable into engagement with said abutment means for locking said wheel to said axle.

40 6. In an earth scraper having a back dump means, the combination of: a bowl; axles extending outward from said bowl; a draft frame connected to said axles; wheels rotatable on said axles; and latch means positioned between said bowl and one of said wheels for locking said last named wheel from rearward rotation relative to the axle on which it is mounted when said last named wheel is rotated in a rearward direction.

7. In an earth scraper, the combination of:
a bowl; axles extending outward from said bowl;
a draft frame connected to said axles; wheels
rotatable on said axles inside said draft frame;
a pivot eccentrically supported by said bowl; a
latch on said pivot having a forwardly faced
shoulder and being swingable between latched

and unlatched positions; and an abutment on
one of said wheels having a rearwardly faced
shoulder engageable with said latch when said
latch is in latched position to transmit rearward
5 rotation from said wheel to said bowl.
